UNITED STATES PATENT OFFICE

2,541,035

STITCH PICKER

Artis Elmer Charles, Guntersville, Ala., assignor
to Carolyn Chenilles, Inc., New York, N. Y., a
corporation of New York

Application April 2, 1947, Serial No. 738,847

7 Claims. (Cl. 112—79)

1

This invention relates to a machine for simultaneously producing a plurality of spaced tufts on a web of textile fabric, and relates more particularly to an improved stitch picker for use in connection with such tufting machine.

In my Patent No. 2,432,469, I have shown and described certain novel improvements on the multiple needle tufting machine shown and described in Patent No. 2,335,487 to Cobble, et al., whereby the tufts may be spaced longitudinally of the fabric web a predetermined distance from each other. It is an important object of this invention to provide an attachment for the improved tufting machine described in my said patent to pick or remove from the fabric web certain undesirable stitches.

Other objects of this invention, together with certain details of construction and combinations of parts, will appear from the following detailed description and will be pointed out in the appended claims.

In the drawings, wherein a preferred embodiment of my invention is shown:

Fig. 1 is a rear elevational view of a multiple needle tufting machine showing my attachment applied thereto;

Fig. 2 shows two views of the picker finger; and
Fig. 3 shows two views of the presser finger.

Like reference numerals indicate like parts throughout the several views of the drawings.

Since the multiple needle tufting machine to which my attachment is applied is fully shown and described in the abovementioned Cobble, et al. patent, I will describe this well-known tufting machine only to such extent as is necessary properly to disclose the present invention.

Referring to Fig. 1 of the drawings, the reference numeral 4 indicates the framework of the tufting machine at the top of which is journaled in bearings such as bearing 5 a drive shaft 6. At is known, this drive shaft, through suitable connecting mechanism, actuates all of the function elements of the tufting machine such as, for example, the reciprocating needle bar, the looping and loop cutting mechanism, and the fabric web feed mechanism.

The feed mechanism is substantially the same as that shown in the Cobble et al. patent, being mounted at the back of the tufting machine, and comprises a feed shaft 7 which is journaled in bearings, such as bearing 8, attached to the framework of the machine. Along the shaft 7 are fixed in any desired spaced relationship a plurality of serrated or toothed discs 9 over which the fabric web 11 is trained after it is fed past the

2

needle bank of the machine. For holding the fabric web being tufted against the serrated discs 9, there are provided a plurality of grippers 12, one for each serrated disc, which are mounted on a bar 13 extending substantially across the width of the machine. The bar 13 is fixed to a rod rotatably mounted in suitable bearings 14 fixed to the framework of the machine. A handle 15 is fixed to rod to which bar 13 is fixed and is adapted to move simultaneously all of the grippers 12 relative to the serrated discs 9. As shown in Fig. 1, all of the grippers are in raised position, i. e., away from the serrated discs. To place grippers 12 in operative position, handle 15 is manually lowered from the position shown in Fig. 1, whereupon bar 13 is rotated, causing the grippers 12 to move over the serrated or toothed discs 9 for the purpose of holding the fabric web 11 in contact with said discs, as is well known in the art.

20 The feed shaft 7, as is described in the said Patent No. 2,432,469, may be intermittently rotated to feed the fabric web 11 a stitch length at a time to form a tuft containing the desired number of stitches or loops and then have an auxiliary 25 rotation given thereto so as to cause the fabric web to be moved a distance greater than a stitch length. Thus there is provided between the tufts a space of any desired length.

As is known, the loops forming the tufts are severed, as formed, by suitable cutting mechanism. Where the tufts are spaced on a fabric web, a length of yarn bridges the space between the tufts on the reverse or stitch side of the fabric web. This length of yarn, indicated by reference numeral 16 in Fig. 1, comprises part of the last loop in the tuft and part of the first loop of the next succeeding tuft. When the loops are cut, this length of yarn is free to be removed and has usually been removed by hand. In accordance 35 with this invention, these lengths of yarn 16 are removed automatically by my novel attachment, which will now be described.

The means for removing the lengths of yarn 16 comprise a rigid picker finger 17 of any suitable material, preferably steel and presser fingers 18 of any suitable flexible material such as brass, a picker finger 17 cooperating with a presser finger to remove the yarn 16, as will hereinafter be described. The picker finger is formed with a 40 curved portion 19 at its lower extremity and the upper half thereof is twisted at right angles to the lower portion. The upper portion is bifurcated at 21 to fit over a screw 22 by which it is adjustably held in a bar 23. The resilient presser finger 18 is provided with a curved portion 24 at

the lower extremity thereof. The upper part of the resilient presser finger is at an angle to the lower part thereof. The resilient presser fingers are held in a bar 25 in such a manner that the curved portion 24 of each presser finger is in the same vertical plane as the curved portion 19 of each picker finger.

Bar 25, on which the resilient presser fingers are mounted, is fixed and bar 23, on which the picker fingers are mounted, is pivotally attached to bar 25 by links 26 and is adapted to be moved relative to said bar 25. To this end one extremity of bar 23 is provided with a cam follower 27 which is adapted to be received in a groove 28 of a gear 29, mounted on a stub-shaft 30, meshing with and rotated by a gear 31 fixed, as by a collar 32 and pin 33, to the drive shaft 6 of the tufting machine. Set in a portion of groove 28 is a raised cam 34. At a predetermined time, the rotation of gear 29 brings the cam 34 around to contact the cam follower 27, which is kept in contact with groove 28 and cam 34 by springs 35. Cam 34 causes bar 23 to move to the right as shown in Fig. 1, thus moving gripper fingers 17, which are normally in the position shown in broken lines, toward stationary presser fingers 18 in an arcuate path.

In its movement toward the right, the curved portion 19 of the gripper fingers 17 catches the length of yarn 16, as the fabric web passes over the table 36 of the tufting machine, and presses the yarn into contact with the curved portion 24 of the resilient presser finger 18. The cooperative movement of the fingers 17 and 18 pulls the length of yarn 16 an appreciable distance out of the fabric web and movement of the fabric web by the rotation of the serrated discs 9 on the feed shaft 7 completes the removal of the length of yarn from the fabric web.

The cam on gear 29 driven by drive shaft 6 synchronizes the movement of bar 23 with the movement of the tufting operation of the machine.

It is believed that the operation of my novel attachment will be apparent from the above description.

The embodiment of my invention shown and described herein is to be considered merely as illustrative, as my invention is susceptible to variation, modification and change within the spirit and scope of the appended claims.

What is claimed is:

1. In a machine for forming in a fabric web being fed therethrough a plurality of spaced tufts composed of a predetermined number of cut loops of yarn and joined by a length of yarn, means for removing said length of yarn comprising a stationary resilient finger and a movable rigid finger cooperating with said stationary finger to hold said length of yarn therebetween for a predetermined length of time.

2. In a machine for forming in a fabric web being fed therethrough a plurality of spaced tufts composed of a predetermined number of cut loops of yarn and joined by a length of yarn, means for removing said length of yarn comprising a stationary resilient finger and a movable rigid finger cooperating with said stationary finger to hold said length of yarn therebetween for a predetermined length of time, and means operatively connected to said machine for moving said rigid finger.

3. In a machine for forming in a fabric web being fed therethrough a plurality of spaced tufts composed of a predetermined number of cut loops of yarn and joined by a length of yarn, means for removing said length of yarn comprising a stationary resilient finger, a movable rigid finger, a bar for holding said rigid finger, and means operatively connected to said machine for moving said bar to cause said rigid finger to move toward and cooperate with said resilient finger to hold said length of yarn therebetween for a predetermined length of time.

4. In a machine for forming in a fabric web being fed therethrough a plurality of spaced tufts composed of a predetermined number of cut loops of yarn and joined by a length of yarn, means for removing said length of yarn comprising a stationary resilient finger, a movable rigid finger, a bar for holding said rigid finger, and a cam operated by said machine for moving said bar to cause said rigid finger to move toward and cooperate with said resilient finger to hold said length of yarn therebetween for a predetermined length of time.

5. In a machine for forming in a fabric web being fed therethrough a plurality of spaced tufts composed of a predetermined number of cut loops of yarn and joined by a length of yarn, means for removing said length of yarn comprising a stationary resilient finger, a movable rigid finger, a bar for holding said rigid finger, a cam for moving said bar to cause said rigid finger to move toward and cooperate with said resilient finger to hold said length of yarn therebetween for a predetermined length of time, and a gear operated by said machine for rotating said cam.

6. In a machine for forming in a fabric web being fed therethrough a plurality of spaced tufts composed of a predetermined number of cut loops of yarn and joined by a length of yarn, means for removing said length of yarn comprising a stationary resilient finger, a movable rigid finger, a bar for holding said rigid finger, a cam for moving said bar to cause said rigid finger to move toward and cooperate with said resilient finger to hold said length of yarn therebetween, and a gear rotated by the drive shaft of the machine for rotating said cam.

7. In a machine for forming in a fabric web being fed therethrough a plurality of spaced tufts composed of a predetermined number of cut loops of yarn and joined by a length of yarn, means for removing a plurality of lengths of yarn simultaneously comprising a plurality of stationary resilient fingers, a movable rigid finger cooperating with each of said resilient fingers, a bar for holding said rigid fingers, a cam for moving said bar to cause said rigid fingers to move toward and in contact with said resilient fingers to hold the lengths of yarn therebetween and a gear operated by said machine for rotating said cam.
